C. DORNIER

TWIN MOTOR FLYING MACHINE

Filed June 28, 1920

INVENTOR:

Claude Dornier.

UNITED STATES PATENT OFFICE.

CLAUDE DORNIER, OF FRIEDRICHSHAFEN-ON-THE-BODENSEE, GERMANY.

TWIN-MOTOR FLYING MACHINE.

Application filed June 28, 1920. Serial No. 392,565.

(GRANTED UNDER THE PROVISIONS OF THE ACT OF MARCH 3, 1921, 41 STAT. L., 1313.)

To all whom it may concern:

Be it known that I, CLAUDE DORNIER, a citizen of the German Empire, residing at Friedrichshafen-on-the-Bodensee, Germany, 5 have invented certain new and useful Improvements in Twin-Motor Flying Machines (for which I have filed application in Germany, July 29th, 1918), of which the following is a specification.

10 My invention refers to flying machines and more especially to such machines as carry two motors.

If the motor foundation is built up on the forward part of the hull, the interior of the latter, besides serving to carry the fuel tanks, can according to my invention, also be utilized for the accommodation of the bomb dropping plant, no matter whether the flying-machine is a multiple-plane or mono-plane. In order not to be obliged, in the latter case, to make the motor foundation too high, the hull is formed with a gap for the rear propeller to work in. A pressure propeller is arranged in the front portion thus formed, whilst the driver or drivers of the flying-machine is or are accommodated in the center or in the rear portion of the hull. This arrangement is particularly suitable for metal flying-machines.

20 In the drawings attached to this specification and forming part thereof a flying-machine embodying my invention is illustrated in a purely diagrammatical manner. In the drawings

25 Fig. 1 is a side elevation, partly in section, whilst

Fig. 2 is a plan view and

Fig. 3 a front elevation, partly in section.

The hull A of the flying machine is subdivided by a gap α extending across the width of the hull, into a forward part A' and a rear part A''. The forward part A' bears a head-piece B joined on by means of a hinge connection b^1 , which forms a joint 40 engine casing for two motors C and C'. The two motors are arranged tandem fashion close to one another in the plane of symmetry of the flying-machine. Their crank-shafts are preferably connected by a clutch 45 (not shown).

The forward motor C operates a traction propeller D and the backward one a pressure propeller D'.

The latter runs in the gap α^1 of the hull

which, if necessary, may be made to form a 55 real pit closed up on the sides by the sidewalls of the hull extending from the forward part to the rear part. The non-interrupted sidewalls of the hull could then be made correspondingly thinner, but the effect of the propeller would be less satisfactory on account of the air being cut off laterally.

To the rear of the gap a larger space and still further back a smaller one are provided 65 for the crew. Windows α^2 and machine-gun breast-works α^3 allow of the necessary view of the surroundings. In the front part A underneath the engine casing, fuel tanks E and below these a bomb-dropping plant F 70 are provided. From the sides of the hull two lower supporting planes G issue forth, whilst an upper supporting plane H is braced by means of stays J against the lower ones and the hull. 75

In order to reduce the air resistance as much as possible the casing B for the motors C and C' is closed on all sides and only provided with ventilating openings b^2 . The covering, however, could also be dispensed with if one is prepared to put up with the increase in air resistance. In the example illustrated it is assumed that plates of light metal are used for the covering and a framework of light metal ribs and ties for the 80 frame of the hull. 85

The whole arrangement could also be made in such a manner that the engine plant as a whole is accommodated underneath the forward part of the hull. In this case, however, a correspondingly lower position of the carriage would become necessary. 90

I wish it to be understood that I do not desire to be limited to the exact details of construction shown and described, for obvious modifications will occur to a person skilled in the art.

I claim:

1. In a flying machine in combination, a hull, accommodation for the driver in said hull and a power plant and a pressure propeller on said hull substantially on a level and in line with and in front of said accommodation. 100

2. In a flying machine in combination, a hull, a pair of motors mounted tandem fashion in the front portion of said hull, a pressure propeller operatively connected 105

with said motors and accommodation for the driver to the rear of said propeller and in line therewith.

3. In a flying machine in combination, a hull subdivided into two distinct portions, a front and a rear portion, a power plant in and a pressure propeller immediately to the rear of said front portion, and accommodation for the driver in said rear portion.

10 4. In a flying machine in combination, a hull subdivided into two distinct portions, a front and a rear portion having their upper parts separated by a gap, a pair of motors mounted tandem fashion in said

15 front portion, a pressure propeller operatively connected with one of said motors and extending into the gap and accommodation for the driver in said rear portion.

20 5. In a flying machine in combination, a hull subdivided into two distinct portions, a front and a rear portion, a power plant in, a bomb throwing plant underneath and

a pressure propeller immediately to the rear of said front portion and accommodation for the driver in said rear portion.

25

6. In a flying machine in combination, a hull subdivided into two distinct portions, a front and a rear portion, two motors mounted tandem-fashion in, a bomb throwing plant underneath, a traction propeller 30 in front and a pressure propeller immediately to the rear of said front portion and accommodation for the driver in said rear portion.

7. In a flying machine in combination, a hull subdivided into two distinct portions, a front and a rear portion, a power plant and a fuel reservoir in, a bomb throwing plant underneath and a pressure propeller 35 immediately to the rear of said front portion and accommodation for the driver in said rear portion.

40

In testimony whereof I affix my signature.
CLAUDE DÖRNIER.
